UNITED STATES PATENT OFFICE.

DAVID C. KLAUSMEYER, OF CINCINNATI, OHIO, ASSIGNOR TO THE CINCINNATI BICK-FORD TOOL COMPANY, OF CINCINNATI, OHIO, A CORPORATION OF OHIO.

STRAP-GUARDED RADIAL DRILL.

Application filed February 10, 1925. Serial No. 8,186.

This invention deals with mechanism for covering the rotating or moving parts of a machine and particularly for protecting the operator of a machine against injury. More 5 specifically the invention is concerned with the covering of rotating members on a drilling machine such for example as the rotating shafts on a radial drill.

In a drilling machine of the radial type, 10 a radial arm is not only movable vertically but is also rotatable about a vertical column or post. A tool head, which is mounted on the arm in any convenient manner, is connected to an arm shaft mounted in the radial 15 arm. A slot is formed in the arm in order to take care of the connection of the head to the arm shaft during the movement of the tool head along the arm. The slot thus formed in the arm exposes the rotating 20 shaft. Not only is the shaft in the arm exposed but in many cases the vertical driving shaft, which is connected to the arm shaft, is left exposed. Although a casing may be provided for the vertical driving shaft it is necessary to form a longitudinal slot in such 25 casing to take care of the connection of the arm shaft to the driving shaft during the vertical movement of the radial arm.

My invention provides means whereby the 30 arm shaft carried by the radial arm is enclosed at all times irrespective of the movement of the tool head along the arm. Moreover, provision is made in my invention for enclosing the vertical driving shaft without 35 interfering with the vertical movement of the radial arm.

Preferably, in safe-guarding the rotating arm shaft in a radial drill, in accordance with my invention, a flexible covering composed of suitable material is connected to the 40 radial arm and to the tool head in such a manner as to cover the usually exposed part of the arm shaft. In carrying out my invention two flexible strips may be each fixedly 45 connected at one end either to the end of the slot in the arm or to the head as desired. If the end of one strip is connected to the arm at the end of the slot, the other end of the strip is adjustably connected to the tool head 50 so as to maintain the strips taut during the movement of the head along the arm. One means of adjustably connecting the strip may be a drum normally under tension. A force may be normally exerted on the 55 drum tending to wind the strip upon it. The

flexible strip at the opposite side of the tool head may be connected to the head and to the arm in a like manner.

If the vertical driving shaft is provided with a casing having a slot formed in it as 60 above set forth, a flexible covering as above described may be provided for covering the slot to enclose the vertical driving shaft.

Other objects and advantages will be in part indicated in the following description 65 and in part rendered apparent therefrom in connection with the annexed drawings.

To enable others skilled in the art so fully to apprehend the underlying features hereof that they may embody the same in the various ways contemplated by this invention, drawings depicting a preferred typical construction have been annexed as a part of this disclosure and, in such drawings, like characters of reference denote corresponding 70 parts throughout all the views, of which:—

In the accompanying drawings, Figure 1 is an elevational view of a radial drill having the shafts thereon covered in accordance with my invention. Fig. 2 is an end view of 80 the radial arm shown in Fig. 1. Fig. 3 is a sectional view along the line 3—3 of Fig. 1. Fig. 4 is a sectional view along the line 4—4 of Fig. 1 and Fig. 5 is an end sectional view of a wind drum mounted on the head. 85

Referring to the accompanying drawings, a radial drill is illustrated comprising a sleeve member 1 which is rotatably mounted on a post or column 2. The sleeve member 2 carries a radial arm 3 which in turn carries 90 a suitable tool head 4. The arm 3 is supported on the sleeve 1 by means of a girdle 5 and is adapted to have vertical movement, in the usual manner, on the sleeve.

An arm shaft 7, which is rotatably mounted within the radial arm 3, is provided for operating the tool carried by the head 4. Suitable mechanism 8 comprising a shaft and bevelled gear wheels project through a slot 9 in the arm 3 for connecting the operating parts of the head to the arm shaft 7. The slot 9 in the radial arm takes care of the connecting mechanism 8 during the movement of the head along the arm. However, it will be noted the slot leaves the rotating 100 shaft 7 exposed.

The arm shaft 7 carries a bevelled gear wheel 10 which meshes with a bevelled gear wheel 11 on a vertical driving shaft 12. The bevelled gear wheel 11 has a splined connec- 110

tion with the vertical driving shaft 12 and is supported by an arm 13 which projects from the arm 3. The vertical driving shaft is connected by suitable gearing 12^a to the 5 main driving shaft located within the post or column 2. The gearing 12^a also serves to operate a shaft 14 for moving the arm 3 along the sleeve.

In a radial drill constructed in accordance 10 with my invention, the vertical driving shaft 12 is enclosed completely at all times irrespective of the movement of the arm 3 along the sleeve 1. A casing 16, which is supported by brackets 17 and 18 at the bottom 15 and the top of the sleeve 1, encircles the vertical driving shaft 12 and is provided with a slot 17 therein. The slot 17 in the casing 16 takes care of the arm shaft 12 during the vertical movement of the radial 20 arm. However, unless special provision is taken for covering the slot 17, the vertical driving shaft 12 will be exposed at all times. In order to maintain a covering on the slot 25 17, a strip 20, which may be composed of fabric, metal or other suitable material, as desired, is stretched and held taut between the arm 3 and the upper end of the slot 17. A similar strip of flexible material 21 is connected between the lower side of the arm 3 30 and the lower end of the slot 17. In like manner, two flexible strips 22 and 23 are provided for covering the slot 9 which is formed in the radial arm 3.

Inasmuch as the four strips 20, 21, 22 and 35 23 are similar in construction and operation a detailed description of only one strip and its connection to the radial drill will be given in detail. The strip 23 on the arm 3 is fixedly connected to the arm at the inner end of 40 the slot 9 by means of set screws 25. From the fixed connection, the strip extends along the slot 9 to the head 4. At the head 4 the strip 23 passes under a roller 27, as shown in Figs. 1 and 4 to a winding drum 28. The roller 27 is rotatably mounted on a 45 shaft 29 which is fixed to the head 4 as shown in Fig. 4 of the drawings. The winding drum 28 is rotatably mounted on a shaft 30 which is fixedly mounted on the head 4. The strip 23 is secured to the drum 28 and suitable means is provided for exerting a force normally tending to wind the strip upon the drum. In the drawings a spring member 31 is shown connected between the drum 28 and the supporting shaft 30. The spring member 31 exerts a force 50 tending to rotate the drum 28 in a clockwise direction as viewed in Fig. 1 of the drawings.

The flexible strip 22 on the opposite side 60 of the head 4 is connected to the arm 3 by set screws 33 at the opposite end of the slot 9. The strip 22 extends along the slot 9 under a roller 34, similar to the roller 27, 65 and to a drum 35 which is similar in con-

struction to the drum 28 heretofore described. However, the spring located within the drum 35 is so set as to exert a force tending to rotate the drum in a counter-clockwise direction. When the strips 22 and 70 23 are so mounted on the arm 3, a covering is provided for the slot 9 irrespective of the movement of the head 4 along the arm. The spring members in the drums 28 and 35 maintain the strips 22 and 23 taut at all 75 times. It will be noted that if so desired the strips 22 and 23 may be fixedly mounted on a head 4 and the drums 28 and 35 may be mounted on the arm 3 at the ends of the slot 9.

The strip 20, which covers the upper part of the slot 17 formed in the casing 16, is shown fixedly connected by set screws 37 to the arm 3. The strip 20 extends from the fixed connection along the slot to a drum 38. 80 The drum 38, which is preferably mounted on the bracket 18, is similar in construction and operation to the drum 28 heretofore described. A guide roller 39 is provided adjacent to the drum 38. The strip 21 is fixedly connected to the lower side of the arm 3 by means of set screws 40. The opposite end of the strip 21 passes around a guide roller 41 to a wind drum 42. The winding drum 42 is similar in construction and operation 85 to the winding drum 28 heretofore described. Although the strips 20 and 21 are shown fixedly connected to the arm and the drums 38 and 42 are shown mounted at the ends of the slot 17, it is to be understood that if 90 so desired the winding drums 38 and 42 may be carried by the arm 3.

Without further analysis, the foregoing will so fully reveal the gist of this invention that others can, by applying current knowledge, readily adapt it for various utilizations by retaining one or more of the features that, from the standpoint of the prior art, fairly constitute essential characteristics of either the generic or specific aspects of 100 this invention and, therefore, such adaptations should be, and are intended to be, comprehended within the meaning and range of equivalency of the following claims:

Having thus revealed this invention, I 115 claim as new and desire to secure the following combinations and elements, or equivalents thereof, by Letters Patent of the United States:

1. In a radial drill structure, the combination comprising a radial arm; an arm shaft mounted in said arm; a tool head movable along said arm and connected to the arm shaft through a longitudinal slot formed in the arm; a flexible covering or 120 strip connected to the arm at one end of said slot and extending along the slot to the head; a drum mounted on said head and connected to said flexible strip; means exerting a force on said drum tending to wind 125 130

the flexible strip upon it; and a similar strip, drum and winding means located on the opposite side of the head.

2. In a radial drill structure, the combination comprising a radial arm movable along and rotatable about a column; an arm shaft mounted in said arm; a tool head movable along said arm and connected to the arm shaft through a longitudinal slot 5 formed in the arm; a flexible strip connected to the arm at one end of said slot and extending along the slot to the head; a drum mounted on said head and connected to said flexible strip, said drum being under tension 10 tending to wind the strip upon it; a vertical driving shaft connected to said arm shaft; a casing surrounding said driving shaft and having a slot formed therein to permit the arm shaft to extend into the casing; a flexible strip connected to the casing at one end of the slot; and a drum mounted on said arm and connected to the flexible strip on said casing, said arm drum being under tension 15 tending to wind the strip upon it.

25 3. In a radial drill, the combination comprising a supporting member having a slot formed therein; operating mechanism movable along said supporting member and extending through said slot into the supporting member; and means connected to the operating mechanism and extending along the slot in the supporting member to the end of the slot for entirely covering said slot 20 in all positions of the operating mechanism.

35 4. A radial drill structure combining a column formed with a slot extending in the direction of its length; a radial arm supported by the column and slideable lengthwise thereof, said arm being formed with a slot extending lengthwise thereof; a tool head slidably mounted on said arm and having a portion extending through said slot; a driving shaft extending lengthwise of the column; a shaft extending lengthwise of the 40 arm; said arm shaft extending through the

slot in the column and being operatively connected to the driving shaft; means connected to the head, and extending along the slot in the arm, for entirely covering the last named slot in all positions of the head 50 on the arm; and means connected to the arm and extending along the slot in the column for entirely covering the last named slot in all positions of the arm on the column.

5. In a radial drill structure, the combination comprising a rotatable sleeve; a radial arm mounted to have sliding movement on said sleeve; a vertical shaft mounted on said sleeve; an arm shaft mounted in said radial arm and connected to said vertical 55 shaft; a casing enclosing said vertical shaft and having a slot formed therein, said slot serving to permit the free vertical movement of the arm shaft; and flexible means secured to the arm and extending along the slot in 60 the casing to the end of the slot for entirely covering the slot in the casing in all positions of the arm on the sleeve.

6. In a radial drill structure, the combination comprising a rotatable sleeve; a radial 70 arm mounted to have sliding movement on said sleeve; a vertical shaft mounted on said sleeve; an arm shaft mounted in said radial arm and connected to said vertical shaft; a drill head movable along the radial arm; a longitudinal slot formed in the arm for permitting the head to engage said arm shaft; a casing enclosing said vertical shaft and having a slot formed therein, said slot serving to permit the free vertical movement of 75 the arm shaft; flexible means secured to the arm and to said casing for covering the slot in the casing irrespective of the movement of the arm along the sleeve; and flexible means secured to the arm and to said head 80 for covering the slot in said arm irrespective of the movement of the head along the arm.

In witness whereof, I have hereunto subscribed my name.

DAVID C. KLAUSMEYER.
